(57) **ABSTRACT**

A moistening system that significantly reduces the problems caused by contaminants in the moistening fluid is provided. The catch basin of a moistening system is provided with a filter that reduces the amount of contaminants contained in the recycled moistening fluid. Additionally, the moistening fluid is buffered with an acid that acts to dissolve the paper filler and other soluble debris that may be introduced into the moistening fluid, thereby significantly decreasing any blinding of components of the moistening system that would otherwise reduce the flow rate of the moistening fluid through the system. These ensure that sufficient moistening fluid is applied to the envelope flaps, which results in consistent and complete sealing of the envelope flaps.

**MOISTENING SYSTEM FOR ENVELOPES
THAT REDUCES CLOGGING CAUSED BY
CONTAMINANTS**

FIELD OF THE INVENTION

The invention disclosed herein relates generally to moistening systems such as those used in mailing systems to seal envelope flaps, and more particularly to a moistening system that prevents clogging of components thereof.

BACKGROUND OF THE INVENTION

Mailing systems, such as, for example, a mailing machine, often include different modules that automate the processes of producing mail pieces. The typical mailing machine includes a variety of different modules or sub-systems each of which performs a different task on the mail piece. The mail piece is conveyed downstream utilizing a transport mechanism, such as rollers or a belt, to each of the modules. Such modules could include, for example, a singulating module, i.e., separating a stack of mail pieces such that the mail pieces are conveyed one at a time along the transport path, a stripping/moistening module, i.e., stripping open the flap of an envelope, wetting and sealing the glued flap of an envelope, a weighing module, and a metering/printing module, i.e., applying evidence of postage to the mail piece. The exact configuration of the mailing machine is, of course, particular to the needs of the user. Other types of mailing systems, such as, for example, inserters, feed material from one or more trays to be inserted into awaiting envelopes whose flaps have been opened and then sealed when the contents have been inserted.

Typically, a stripping device includes a structure for deflecting a flap of a moving envelope away from the envelope's body to enable the moistening and sealing process to occur. The deflecting structure typically includes a stripper blade that becomes inserted between the flap of the envelope and the body of the envelope as the envelope traverses the transport deck of the mailing machine. Once the flap has been stripped, a moistening device moistens the glue line on the envelope flap in preparation for sealing the envelope. Typically, a moistening fluid is deposited onto the envelope flap to activate the glue. The flap is then closed and sealed, such as, for example, by passing the closed envelope through a nip of a sealer roller to compress the envelope and flap together, and the envelope passed to the next module for continued processing.

In typical moistening applications, it is desirable to maintain a catch basin beneath the moistening device to collect moistening fluid that is discharged by the moistening device but not carried away by the envelope. Preferably, this moistening fluid is recycled and stays within the moistening device for subsequent usage. Unfortunately, this fluid becomes contaminated with different materials derived from the paper and adhesive. Contaminants include, for example, envelope adhesive and paper dust, comprising paper fibers and filler used to make paper envelopes, which are released by the friction associated with the envelope contacting different parts of the mailing system, such as the stripper/moistening module. Such contaminants negatively impact the operation of the moistening device such as, for example, clogging of components that supply the moistening fluid to the different parts of the moistening device. These situations

2

can result in insufficient moistening fluid being applied to the envelope flaps, which results in inconsistent sealing of the envelopes.

5 SUMMARY OF THE INVENTION

The present invention alleviates the problems associated with the prior art and provides a moistening system that significantly reduces the problems caused by contaminants 10 in the moistening fluid.

In accordance with the present invention, the catch basin of a moistening system is provided with a filter that reduces the amount of contaminants contained in the recycled moistening fluid. Additionally, the moistening fluid is buffered 15 with an acid that acts to dissolve the paper filler and other soluble debris that may be introduced into the moistening fluid, thereby significantly decreasing any blinding of the filter or other components that would otherwise reduce the flow rate of the moistening fluid through the system. These 20 ensure that sufficient moistening fluid is applied to the envelope flaps, which results in consistent and complete sealing of the envelope flaps.

Therefore, it should now be apparent that the invention substantially achieves all the above aspects and advantages.

25 Additional aspects and advantages of the invention will be set forth in the description that follows, and in part will be obvious from the description, or may be learned by practice of the invention. Moreover, the aspects and advantages of the invention may be realized and obtained by means of the 30 instrumentalities and combinations particularly pointed out in the appended claims.

DESCRIPTION OF THE DRAWINGS

35 The accompanying drawings illustrate presently preferred embodiments of the invention, and together with the general description given above and the detailed description given below, serve to explain the principles of the invention. As shown throughout the drawings, like reference numerals 40 designate like or corresponding parts.

FIG. 1 illustrates a mailing machine in which the moistening system of the present invention can be utilized;

FIG. 2 illustrates a portion of a moistening system according to the present invention;

45 FIG. 3 illustrates a portion of another moistening system according to the present invention; and

FIG. 4 is a graph illustrating the resistive flow rates of exemplary filters when tested with conventional moistening fluid and a moistening fluid according to the present invention.

**50 DETAILED DESCRIPTION OF THE PRESENT
INVENTION**

55 In describing the present invention, reference is made to the drawings, wherein there is seen in FIG. 1 a mailing machine 10 that includes a moistening system according to the present invention. Mailing machine 10 comprises a base unit, designated generally by the reference numeral 14, the 60 base unit 14 having a mail piece input end, designated generally by the reference numeral 16, and a mail piece output end, designated generally by the reference numeral 18. A control unit 20 is mounted on the base unit 14, and includes one or more input/output devices, such as, for example, a touch-screen display device 24. One or more cover members 26 are pivotally mounted on the base 14 so as to move from the closed position shown in FIG. 1 to an

open position (not shown) to expose various operating components and parts for service and/or repair as needed.

The base unit **14** further includes a horizontal feed deck **30** which extends substantially from the input end **16** to the output end **18**. A plurality of nudger rollers **12** are suitably mounted under the feed deck **30** and project upwardly through openings in the feed deck so that the periphery of the rollers **12** is slightly above the upper surface of the feed deck **30** and can exert a forward feeding force on a succession of mail pieces placed in the input end **16**. A registration wall **32** defines a mail piece registration surface substantially perpendicular to the feed deck **30** that extends substantially from the input end **16** to the output end **18**. Mail pieces placed in the input end **16** are fed by the nudger rollers **12** along the feed deck **30**, with the top edge of the mail piece being registered against the wall **32**. The mail pieces may be passed through one or more modules, such as, for example, a singulator module and a moistening module that includes a moistening system according to the present invention as described below. Each of these modules is located generally in the area indicated by reference numeral **36**. The mail pieces are then passed to a metering/printing module located generally in the area indicated by reference numeral **38**.

FIG. 2 illustrates in block diagram form a moistening system **50** according to an embodiment of the present invention. System **50** includes a replaceable bottle **52** that can be inserted into a reservoir **54**. Reservoir **54** is preferably mounted in, for example, the base unit of the mailing machine **10**. Under normal operation, moistening fluid contained in the bottle **52** empties into the reservoir **54**. The reservoir **54** supplies the moistening fluid via tubing **56** to a pump **58** and a well **60**. Pump **58**, via tubing **62**, supplies the moistening fluid to a moistening device **70**. Moistening device **70** includes a wetting element **72**, typically formed from a contact media such as foam or felt, which is secured to the trailing edge of a stripping blade (not shown). The wetting element **72** is supplied with moistening fluid, through physical contact with a wick **74**, a portion of which is located in the moistening fluid **80** contained in the well **60**, and capillary action of the moistening fluid. The wetting element is also supplied with moistening fluid via the pump **58** which supplies the moistening fluid to a discharge device **76** that includes a series of openings or nozzles to distribute moistening fluid onto the wetting element **72**.

FIG. 3 illustrates in block diagram form a second moistening system **50'** according to an embodiment of the present invention. System **50'** is similar to system **50** in that it includes a replaceable bottle **52** that can be inserted into a reservoir **54**. Reservoir **54** is preferably mounted in, for example, the base unit of the mailing machine **10**. Under normal operation, moistening fluid contained in the bottle **52** empties into the reservoir **54**. The reservoir **54** supplies the moistening fluid via tubing **56** to a well **60**. Moistening device **70'** includes a wetting element **72**, typically formed from a contact media such as foam or felt, which is secured to the trailing edge of a stripping blade (not shown). The wetting element **72** is supplied with moistening fluid, through physical contact with a wick **74**, a portion of which is located in the moistening fluid **80** contained in the well **60**, and capillary action of the moistening fluid. It should be noted that the wick **74** and wetting element **80** need not be separate items, and instead the wick **74** can be integrated with the wetting element **72**, or a portion of the wetting element **80** can act as a wick and be located in the moistening fluid **80** contained in the well **60**.

As an envelope passes through the moistening device **70** or **70'**, the inside of the envelope flap, where the glue line for

sealing the flap is located, contacts the wetting element **72**, such that the wetting element **72** transfers moistening fluid to the flap to activate the glue. The moistening device **70** and **70'** illustrated in FIGS. 2 and 3 are contact moistening systems, in which moistening fluid is deposited onto the glue line on a flap of an envelope by contacting the glue line with a wetting element. It should be understood, however, that moistening device **70** of FIG. 2 could also be a non-contact moistening device, in which moistening fluid is sprayed directly onto the envelope flap with a nozzle and mechanical pump system. The mechanical pump is supplied with moistening fluid from a reservoir and sprays the fluid through the nozzles and onto the envelope flap.

Regardless of whether the moistening device **70** is a contact or non-contact, the well **60** beneath both types of moistening devices **70** and **70'** collects moistening fluid that is discharged by the moistening device **70**, **70'** but not carried away by the envelope. This moistening fluid in the system **50** is recycled and stays within the moistening system **50** for subsequent usage via tube **56**, while the moistening fluid in the system **50'** is recycled by again coming in contact with the wick **74**. Unfortunately, this recycled fluid becomes contaminated with different materials derived from the paper and adhesive. Contaminants include, for example, envelope adhesive and paper dust comprising paper fibers and filler used to make paper envelopes, which are released by the friction associated with the envelope contacting different parts of the mailing system, such as the stripper/moistening module. Such contaminants negatively impact the operation of the moistening system **50** such as, for example, by clogging of the pump **58**, tubing **62**, discharge device **76**, or nozzles in a non-contact system. These situations can result in insufficient moistening fluid being applied to the envelope flaps, which results in inconsistent sealing of the envelopes. To prevent such clogging in the system **50**, a filter pad **90** is provided at the junction between the well **60** and tubing **56**. Filter pad **90** is preferably a rectangular cuboid comprised of woven polyester fibers. The fiber orientation is primarily homogenous, which allows the moistening fluid to freely pass through in multiple directions, but will catch contaminants. Thus, while the moistening fluid will freely pass through the filter pad **90**, a majority of any contaminants contained within the moistening fluid in the well **60** will be trapped by the filter pad **90**, thereby keeping the other moistening system components, e.g., pump **58**, tubing **62**, discharge device **76**, free from contaminants which can cause clogging.

Utilizing the filter pad **90** can resolve many of the problems associated with the clogging of the moistening device **70**. However, a frequent cause of moistener system failure is the collection of contaminants on the filter pad such that the moistening fluid can no longer pass through the filter pad **90** (referred to as blinding of the filter pad). In addition, although the filter pad **90** can remove a large portion of the contaminants, any amounts that do pass through the filter pad **90** can eventually lead to blinding of the wetting element **72**. For system **50'**, the collection of contaminants on the wick **74** and wetting element eventually lead to blinding of the wick **74** and wetting element **72**. It was unexpectedly found that a weak acid-buffered moistening solution maintained flow rate through the filter, thus greatly increasing the filter life. Additionally, blinding of the wick **74** and wetting element **72** was significantly reduced. This was unexpected because paper fibers are not soluble in weak acids. The present inventors have surmised that the majority of the contamination is caused by carbonate paper fillers, which are soluble in weakly acidic solutions. To prevent such blinding,

the moistening fluid is preferably buffered to an acidic pH using an appropriate acid buffer. Typical moistening fluids consist of distilled water, a biocide (to prevent biological growth) and a dye. Other ingredients may also include alcohol detergent and a fragrance. In accordance with the present invention, the pH of the moistening fluid is preferably buffered to approximately 3.0. The acid buffer could be, for example, citric acid, citric acid/sodium citrate, potassium hydrogen phthalate/hydrochloric acid, acetic acid, acetic acid/sodium acetate, hydrochloric acid/sodium citrate, etc. The acid buffer works to dissolve the paper filler and other soluble debris that may be introduced into the moistening fluid. The general composition of two exemplary moistening fluids are provided in Table 1 below.

TABLE 1

Moistening Solution Formulation With Acid Buffers Buffer Strength = 10 mM		
Citric Acid Buffered	Acetic Acid Buffered	
Water	97.7699776	Water
Biocide	0.0000064	Biocide
Dye	0.0000160	Dye
Citric Acid	1.8000000	Acetic Acid
Sodium Citrate	0.4300000	Sodium Acetate
Total	100.0	100.0

FIG. 4 illustrates the resistive flow rates of exemplary filters when tested with conventional moistening fluid (no acid buffer added) and a moistening fluid according to the present invention (with acid buffer added). The test was performed as follows: (1) Two 1 L fluids of 0.5% and 0.464% adhesive and dust were made, one in conventional moistening fluid and the other in a moistening fluid buffered with 1.5% Citric acid. (2) Pads and pumps were set up for each fluid. (3) Baseline cup and resistive tests were taken before the start. (4) Each set was set-up to re-circulate the fluid from the beaker to the pad. (5) Pumps were run until there was a significant drop in resistive test. (6) Resistive measurements were taken periodically during exposure. (7) Final resistive and cup tests were taken for comparison. Table 2 illustrates the test results.

TABLE 2

Flow rate (g/sec)		
	Pad #1—Acid	Pad #2—No Acid
Baseline Average		
Cup:	0.786	0.699
Resistive:	0.621	0.386
Post-Exposure Average		
Cup:	0.686	0.543
Resistive:	0.511	0.034
Cup Performance Drop	-13%	-22%
Total Performance Drop	-18%	-91%
Resulting Drop due to Pad	-5%	-69%

As can be seen from the graph in FIG. 4, the flow rate of the filter that was tested with the moistening fluid having the acid buffer dropped from 0.61 g/sec to approximately 0.51 g/sec. In comparison, the flow rate of the filter that was tested with a conventional moistening fluid (no acid buffer) dropped from approximately 0.39 g/sec to less than 0.05 g/sec. After factoring out pump performance fluctuations, the resulting drop in performance due to pad blinding is 69%

for the moistening fluid without the acid buffer. In contrast, the moistening fluid with the acid buffer only experienced a drop of 5%. By comparing pre- and post-exposure resistive tests, the addition of acid in the moistening fluid indeed significantly improved performance of the filter.

While the present invention has been described with respect to a mailing machine, it should be understood that the present invention is not so limited and can be utilized with any device that has a moistening/sealing system, such as, for example, an inserter and the like. While preferred embodiments of the invention have been described and illustrated above, it should be understood that these are exemplary of the invention and are not to be considered as limiting. Additions, deletions, substitutions, and other modifications can be made without departing from the spirit or scope of the present invention. Accordingly, the invention is not to be considered as limited by the foregoing description but is only limited by the scope of the appended claims.

20 What is claimed is:

1. A moistening system for moistening an envelope flap for sealing of an envelope, the moistening system comprising:

a reservoir to hold moistening fluid;

a moistening device for applying the moistening fluid to a flap of the envelope passing through the moistening system;

a well located beneath the moistening device to collect moistening fluid discharged by the moistening device that is not carried away by the envelope, the well being coupled to the reservoir by a supply tube; and the moistening fluid including an acid buffer, such that the moistening fluid has an acidic pH value, to dissolve paper filler contained in the moistening fluid in the well,

wherein dissolving of the paper filler reduces clogging of the moistening device that can be caused by the paper filler.

2. The moistening system of claim 1, wherein the moistening device is a contact moistening device.

3. The moistening system of claim 1, wherein the moistening device is a non-contact moistening device.

4. The moistening system of claim 1, wherein the moistening fluid has a pH value of approximately 3.0.

5. The moistening system of claim 1, wherein the acid buffer is a citric acid.

6. The moistening system of claim 1, wherein the acid buffer is a citric acid/sodium citrate buffer.

7. The moistening system of claim 1, wherein the acid buffer is a potassium hydrogen phthalate/hydrochloric acid buffer.

8. The moistening system of claim 1, wherein the acid buffer is an acetic acid buffer.

9. The moistening system of claim 1, wherein the acid buffer is an acetic acid/sodium acetate buffer.

10. The moistening system of claim 1, wherein the acid buffer is a hydrochloric acid/sodium citrate buffer.

11. The moistening system of claim 1, further comprising: a pump device coupled to the reservoir by the supply tube, the pump device being coupled to the moistening device to provide moistening fluid to the moistening device.

12. The moistening device of claim 11, further comprising:

a filter to filter the collected moistening fluid that enters the supply tube from the well,

wherein dissolving of the paper filler reduces clogging of the filter and moistening device that can be caused by the paper filler.

13. The moistening system of claim 1, further comprising:
a wick to provide moistening fluid from the well to the 5
moistening device,
wherein dissolving of the paper filler reduces clogging of the wick and moistening device that can be caused by the paper filler.
